UNITED STATES PATENT OFFICE.

EDWARD CHRISTIAN, OF WATERBURY, CONNECTICUT.

PICTURE-FRAME.

No. 855,935.

Specification of Letters Patent.

Patented June 4, 1907.

Application filed February 25, 1907. Serial No. 359,247.

To all whom it may concern:

Be it known that I, EDWARD CHRISTIAN, a citizen of the United States, residing at Waterbury, in the county of New Haven and State of Connecticut, have invented a new and useful Improvement in Picture-Frames; and I do hereby declare the following, when taken in connection with the accompanying drawings, and the letters of reference marked thereon, to be a full, clear, and exact description of the same, and which said drawings constitute part of this specification, and represent, in—

Figure 1 a perspective view of the rear of a picture frame constructed in accordance with my invention. Fig. 2 a transverse sectional view of the same.

This invention relates to an improvement in picture frames, the object being to provide a frame in which a picture may be readily secured and which, if desired, may contain a number of pictures any one of which may be exposed through the front of the frame; and the invention consists in the construction hereinafter described and particularly recited in the claim.

In carrying out my invention, the frame 2 is formed from picture molding of usual construction having a rabbet 3 to extend over the edge of the glass 4. Secured to the back of the frame around the glass is a housing 5. This housing is open at its inner face and preferably provided with a flange 6 which sets into a recess 7 formed for it in the back of the frame around the glass, the housing being secured by screws 8 or otherwise. This housing is rectangular and one end or side is closed by a wall 9. At the opposite end or side a door 10 is secured to the housing by hinges 11 so as to expose the interior of the housing, and this may be held in a closed position by a turn-button 12 secured to the back of the frame. Within the housing and secured to the inner face of the rear wall thereof are two or more longitudinal strips

13 which are adapted to be turned into planes at right angles to the glass. The housing secures the glass to the frame and the picture is inserted into the housing through the door 10 so that the picture is exposed through the glass. When thus located the strips 13 are turned down against it which hold it close to the glass.

If desired, a number of pictures may be placed within the housing, and when desired either one of them may be placed in front of the other so as to be exposed through the front of the frame. Thus provision is made for storing a number of pictures any one of which may, when desired, be placed for exhibition. The strips 13 will clamp against the rearmost picture and hold them all close to the glass.

I claim:

1. The herein described picture frame comprising a frame proper, a housing secured to the back thereof, the housing open at one side, a door secured over said opening, means for holding the door in a closed position, and longitudinal strips hinged to the inner face of said housing, substantially as described.

2. The herein described picture frame comprising a frame proper, said frame formed with a rabbet, a glass located in said frame, a recess formed around said glass, a housing having a flange extending into said recess and secured to the back of said frame, said housing open at one end, a door adapted to close said open end, means for holding the door in a closed position, and longitudinal strips hinged to the inner face of said housing and extending toward said glass, substantially as described.

In testimony whereof, I have signed this specification in the presence of two subscribing witnesses.

EDWARD CHRISTIAN.

Witnesses:

EDWARD MCGRATH,
JOSEPH E. LAUBER.
